UNITED STATES PATENT OFFICE.

JOHN R. ABBOTT, OF COUNCIL BLUFFS, IOWA.

DRILL.

1,278,084.

Specification of Letters Patent. Patented Sept. 10, 1918.

Application filed November 20, 1917. Serial No. 202,993.

To all whom it may concern:

Be it known that I, JOHN R. ABBOTT, a citizen of the United States of America, residing at Council Bluffs, in the county of 5 Pottawattamie and State of Iowa, have invented certain new and useful Improvements in Drills, of which the following is a specification, reference being had therein to the accompanying drawing.

10 This invention relates to a double acting compound hand driven rock drill and has for its object the production of a simple and efficient drill whereby the same may drill two holes at one time and is capable 15 of being adjusted to a desired position in order that the drill may be used for tunnel shaft or stoke work.

Another object of this invention is the production of a simple and efficient drill 20 whereby the bull wheel carrying the hammer will strike as hard a blow in one position as in another position.

With these and other objects in view this invention consists of certain novel constructions, combinations and arrangements of parts as will be hereinafter fully described 25 and claimed.

In the drawings:

Figure 1 is a side elevation of the machine.

Fig. 2 is a front elevation thereof.

Fig. 3 is a top plan view of the machine, certain parts thereof being shown in section.

Fig. 4 is a longitudinal section, taken 35 through the bull casing and the bull wheel supporting casing.

Fig. 5 is a transverse section through the bull wheel supporting casing.

Fig. 6 is an end view of the track frame 40 showing the operating crank supported thereby.

Fig. 7 is a transverse section through the bull casing, the clamp bolts being removed therefrom.

45 Fig. 8 is a side elevation of a pawl operating gear.

Fig. 9 is a longitudinal section through one form of the drill used in connection with the present invention.

Fig. 10 is a transverse section taken 50 through the clamp and water supply member used in connection with the drill shown in Fig. 9.

Fig. 11 is a reduced section taken on line 11-11 of Fig. 3. 55

Fig. 12 is a transverse section through the bracket for supporting the bracing rod.

Fig. 13 is a fragmentary, sectional view of the standard, showing the sections thereof, and the means for connecting the abut- 60

ing sections. By referring to the drawings it will be seen that 1 designates the bull casing which comprises a pair of sections for fitting around the standard 2. These 65

sections of the bull casing 1 are each pro- vided with a projecting lip 3 through which

projecting lip extends a securing bolt 4 for firmly clamping the sections of the bull cas- 70

ing 1 around the standard 2. The sections of the bull casing are provided with concave 75

sockets 5 within which sockets 5 fits the knob 6 of the threaded adjusting rod 7. The sections of the bull casing 1 are seated be- 80

tween the track engaging frames 8 as shown clearly in Fig. 4 of the drawings. These 75

track engaging casings 8 are provided with suitable track engaging knuckles 9 for fit- 85

ting over the longitudinally extending track- rails 10 carried by the track frame 11. This

track frame 11 comprises a plurality of lon- 80

gitudinally extending rods which engage T joints 12 at their outer ends, which T joints

also engage the outer ends of the loop por- 85

tions 13 of the track frame. The loop por- 80

tions 13 carry the drill supporting casings 85

14 to be hereinafter described.

The standard 2 is made up of a plurality of sections and carries a cap 15 at its upper end having suitable spurs 16 formed there- 90

on for engaging or gripping an abutment 90

surface and a suitable cap 17 is carried by the lower end of the standard 2. This 95

standard 2 may be made up of a plurality of sections such as is illustrated in Fig. 13 wherein the two sections 18 and 19 are connected by means of a threaded plug 20 which

threaded plug 20 is provided with squared 95

ends 21 to permit the threading of the plug

into the threaded ends of the sections 18 and 19.

As stated above a drill supporting casing 14 is carried by each of the loop portions 13 and these drill supporting casings 14 are locked upon each clamp between the looped portions 13 by means of the clamping bolts or set screws 22. These drill supporting casings 14 carry rotating sleeves 23 which sleeves firmly grip the drills 24 and rotate the drills as the sleeves 23 are rotated. The drills 24 are preferably keyed to the sleeves 23 to cause the drills to rotate therewith and at the same time permit the drills to have a free longitudinal movement therethrough. Each sleeve 23 carries a ratchet 25 and each ratchet 25 is engaged by means of a pawl 26, the inner ends of these pawls 26 being eccentrically connected to a sprocket wheel 27 by means of their inwardly extending ends 28 as shown clearly in Fig. 8 of the drawings. Each pawl 26 hooks through a casing 29 carried by the drill supporting casings 14 and these pawls 26 are so mounted in the casing 29 as to permit the same to freely move out of engagement with the ratchets 25. A flat spring 30 is carried by each casing 29 and is adapted to normally force the pawl 26 into engagement with the respective ratchets 25. It will be seen that upon each oscillation of the gear 27 the pawls 26 will be reciprocated for gripping the ratchet teeth upon the ratchet 25 and causing the drills 24 to be rotated thereby preventing the drills from becoming stuck in the rock in which the same are being driven. Retaining plates 31 are carried by the casings 14 and overhang the sleeves 23 for firmly holding these sleeves within the casings 14. A chain 32 passes over this sprocket wheel 27 and is secured at one end to the hub of the wheel 35 upon the pins 34 and at the other end to the pin 34' carried by the casing 37.

A sprocket wheel 27' is carried by the end plate 49 and the chain 32 passes over this sprocket wheel 27' as shown in Fig. 11. A coil spring 28' is carried by the chain 32 to keep the same tight over the wheels 27 and 27' and at the same time acts as a return for returning the wheel to its normal position. This bull wheel 35 is keyed to an operating shaft 36 and is adapted to oscillate thereby causing the chain 32 to move forwardly and rearwardly for oscillating the wheel 27 and reciprocating the rods 26.

The wheel 35 is provided with a counterbalance weight 35' formed upon the wheel 35 opposite the hammer 45. The sprocket wheel 27 is carried by the outer end of the track or gaging plates 52 as shown in Fig. 7. The shaft 36 which supports the bull wheel 35 works within the bull wheel supporting the casing 37 and this wheel sup-

porting casing is provided with a plurality of longitudinally extending channels 38 65 which channels fit over the longitudinally extending track rails 10 of the track frame 11 thereby firmly holding the bull wheel supporting casing 37 against accidental removal from the track rails 10. A gear 70 wheel 39 is carried by the shaft 36 and this gear wheel 39 meshes with a segmental rack bar 40 which rack bar is connected to an operating handle 41, the operating handle 41 and rack plate 40 being pivotally mounted 75 upon a pin 42 carried by the supporting arm 43. A coil spring 44 is connected to one end of the handle 41 and at the other end this spring 44 is connected to the gear wheel 39 for causing the gear wheel to return to its 80 normal position after the same has once been rotated by the rack plate 40.

A hammer 45 is carried by the periphery of the bull wheel 35 and this hammer 45 is adapted to swing alternately into engagement with the rear end of the drills 24 the spring 44 acting as a return means for assisting in returning the bull wheel. The rebound of the hammer 45 will also greatly assist the swinging of the bull wheel to its reverse position or operation.

By considering the drawings especially Figs. 1 and 2 it will be seen that the pair of collars 46 are mounted upon the standard 2 and these collars 46 carry links 47 which links in turn engage the bull casing or frame 1. The collars 46 are engaged by means of the bracing rods 48 which rods 48 pass over the end plate 49 carried by the rear ends of the track rods 10. This end plate 49 is provided with a plurality of clamping plates 50 for engaging the rods or cables 48 and firmly holding the same against slipping.

The adjusting rod 7 is threaded through the bull wheel carrying casing 37 and a 105 crank handle 51 is carried by the outer end of this adjusting rod and it should be understood that the bull wheel 35 may be moved forwardly or rearwardly to suit the convenience of the operator by merely the rotation of the crank 51.

By considering Fig. 7 it will be seen that the bull casing 3 carries the track engaging casings 8 as above described, and these track engaging casings are provided with end plates 52 which end plates 52 are provided with apertured ends 53 for fitting over the track rods 10. The track engaging ends 8 as well as the plates 52 are provided with apertures 54 through which the securing 110 bolts 55 pass.

As shown in Figs. 9 and 10 of the drawings the drill 24' may be provided with a longitudinally extending aperture 56 extending toward the outer end 57' of the drill 125 120 in order to permit water to be passed there-

through. The bit 24' is provided with a socket 57^a near its rear end over which socket 57^a fits the clamp 58 of the water supply nozzle 59. This water nozzle 59 is provided with a supply aperture 60 connected with an aperture 61 formed in the bit 24'. A suitable flexible hose 62 may be connected to the nozzle 59 for the purpose of conveying liquid thereto.

10 A bracing rod 63 is carried by the plate 49 by being mounted upon a bracket 64 and this bracket 64 is provided with a swivel end 65 carrying a loop 66. A set screw 67 is carried by the loop 66 for holding the rod 63 in a set position. The rod 63 is adapted to engage the side walls of the mine and brace the rear end of the frame 10.

What is claimed is:

1. A drill of the class described comprising a frame, drilling bits carried thereby, an oscillating bull wheel, and means carried by said oscillating bull wheel for alternately engaging the rear ends of said bits for driving the same into a hard substance.

25 2. A drill of the class described comprising a casing, a bull wheel supporting casing mounted upon said first mentioned casing, means for adjusting said bull wheel supporting casing, drills carried by said first mentioned casing, and means carried by said bull wheel for driving said bits into a hard substance.

30 3. A drill of the class described comprising a frame, a track-way carried upon said frame, a bull wheel supporting casing slidably mounted upon said track-way, drills carried by said frame, and a bull wheel engaging said drills for driving the same into a hard substance.

40 4. A drill of the class described comprising a frame, a bull wheel supporting casing, track-ways mounted upon said frame, said bull wheel supporting casing slidably mounted upon said track-ways, an adjusting rod carried by said frame and engaging said bull wheel supporting frame for moving the same longitudinally upon said track-ways and supporting said wheel in an adjusted position, drills carried by said frame, and means carried by said bull wheel for driving said drills.

45 5. A drill of the class described comprising a frame, a bull wheel supporting casing, track-ways mounted upon said frame, and bull wheel supporting casing slidably mounted upon said track-ways, an adjusting rod carried by said frame and engaging said bull wheel supporting frame for moving the same longitudinally upon said track-ways and supporting said bull wheel in an adjusted position, drills carried by said frame, and means carried by said bull wheel for driving said drills, an operating handle, a gear coöperating with said bull

wheel, and a segment carried by said operating handle and engaging said gear for oscillating said bull wheel.

6. A drill of the class described comprising a frame, a bull wheel supporting casing, track-ways mounted upon said frame, said bull wheel supporting casing slidably mounted upon said track-ways, an adjusting rod carried by said frame and engaging said bull wheel supporting frame for moving the same longitudinally upon said track-ways and supporting said bull wheel in an adjusted position, drills carried by said frame, and means carried by said bull wheel for driving said drills, an operating handle, a gear coöperating with said bull wheel, and a segment carried by said operating handle and engaging said gear for oscillating said bull wheel, a spring for assisting and returning said bull wheel to a neutral position.

7. A drill of the class described comprising a frame, a standard supporting said frame, a bull casing, a track supported upon said bull casing, drills, a bull wheel for operating said drills, a casing supporting said bull wheel, and means for adjusting the position of said bull wheel.

8. A drill of the class described, a frame, a standard supporting said frame, a bull casing, a track supported upon said bull casing, drills, a bull wheel for operating said drills, a casing supporting said bull wheel, and means for adjusting the position of said bull wheel, bracing means secured to said standard and engaging the rear end of said track frame for preventing said track from sagging at its rear ends.

9. A drill of the class described comprising a frame, a track-way formed upon said frame, drill supporting casings carried by said track-way, drills carried by said casings, means for driving said drills, said driving means being movably mounted on said trackway, and means for automatically rotating said drills as the same are driven.

10. A drill of the class described comprising a frame, drill bits, a casing for supporting each drill bit, means for driving said drill bits, ratchets for rotating said drill bits, an oscillating driving wheel, a sprocket for driving said ratchets, a chain passing over said sprocket and connected to said driving wheel, for operating said sprocket as said driving wheel is oscillated.

11. A drill of the class described comprising a frame, drill bits, a casing for supporting each drill bit, means for driving said drill bits, ratchets for rotating said drill bits, an oscillating driving wheel, a sprocket for driving said ratchets, a chain passing over said sprocket and connected to said driving wheel, for operating said sprocket

as said driving wheel is oscillated, a second sprocket, said chain also passing over said second sprocket, and a coil spring carried by said chain.

5 12. A drill of the class described comprising a frame, drills carried thereby, a bracing rod for the rear end of said frame, a bracket carried by the rear end of said frame

and supporting said brace rod, said bracket provided with a swivel end, and a set screw ¹⁰ engaging said brace rod and carried by said swivel end for holding said rod in a set position.

In testimony whereof I hereunto affix my signature.

JOHN R. ABBOTT.
